UNITED STATES PATENT OFFICE.

CLARENCE W. SAWTELLE, OF WINCHENDON, MASS., ASSIGNOR TO HIMSELF,
WILLIAM L. WOODCOCK, AND LESLIE W. WOODCOCK, OF SAME PLACE.

DESIGN FOR A WORK-BOX OR TOILET-CASE.

SPECIFICATION forming part of Design No. 16,811, dated July 20, 1886.

Application filed June 14, 1886. Serial No. 205,149. Term of patent 7 years.

To all whom it may concern:

Be it known that I, CLARENCE W. SAWTELLE, a citizen of the United States, residing at Winchendon, in the county of Worcester, State of Massachusetts, have invented and produced a new and original Design for Work-Boxes and Toilet-Cases, of which the following is a specification, reference being had to the accompanying drawing, forming part thereof.

10 The figure is an isometrical perspective view of my newly-designed box or case, this view being deemed sufficient to fully illustrate my design.

15 My design consists in a work-box or toilet-case representing an organ or similar musical instrument, as fully illustrated in the drawing, in which—

20 A A represent the ends of the box, B the back, C the drawer, D the main lid or cover, and E smaller lids or covers, these parts, when in position, representing parts of the case of a musical instrument. A bank of imitation keys, H, including the black keys or semi-

tones d, is disposed above the drawer C, and imitation pedals J at its lower side and partially in front thereof. The sides A are provided with the ornamental curves x at the top and with the ornamental projections m f at the front, in imitation of portions of an ordinary parlor-organ. The back is provided 30 with a series of ornamental standards, K, and dentals z.

Having thus explained my invention, what I claim is—

25 The design for a work-box or toilet-case 35 herein shown and described, the same comprising the ends A, back K, drawer C, lids D E, and bank of keys H, arranged in imitation of the case, keys, and pedals of an organ or similar musical instrument, substantially as 40 described.

CLARENCE W. SAWTELLE.
